UNITED STATES PATENT OFFICE.

JACOB H. KAPLAN, OF CHICAGO, ILLINOIS.

APPARATUS FOR APPLYING HEAT AND AIR IN DENTAL WORK.

Application filed May 3, 1926. Serial No. 106,237.

This invention relates to an improved apparatus, particularly adapted, though not necessarily limited in its use for applying a blast of heat or of fluid, the apparatus embodying a chamber in which atmospheric air is compressed by mechanical means, and improved means whereby it is possible to secure a sustained or an intermittent blast of fluid at the election of the operator, to produce a steady or an intermittent flame, suitable for use in dental work of any nature where such a blast is necessary or desirable and which apparatus will be of a compact construction and arrangement, easy to be handled and effective and efficient in operation.

A further object is to provide an improved apparatus of this character embodying a fuel chamber and an air chamber, one of which is housed within the other, and a nozzle having communication with the air chamber for directing the blast of air against the flame, and improved means whereby the nozzle may be adjusted with respect to the fuel delivery as may be desired, and maintained in its adjusted position.

To the attainment of these ends and the accomplishment of other new and useful objects as will appear, the invention consists in the features of novelty, in substantially the construction, combination and arrangement of the several parts, hereinafter more fully described and claimed and shown in the accompanying drawings illustrating this invention; and in which

Figure 1 is a vertical longitudinal sectional view of an apparatus of this character constructed in accordance with the principles of this invention.

Figure 2 is an enlarged detail view partly in elevation and partly in section of one form of nozzle.

Figure 3, is an enlarged detail sectional view of the controlling valve shown in Figure 1, with the parts in another position.

Figure 4 is a side elevation of Figure 1.

Figure 5 is a top plan view of the apparatus.

Figure 6 is an enlarged detail sectional view of another form of controlling valve.

Figure 7 is an enlarged detail sectional view showing another form of nozzle, partly broken away and with parts omitted.

Referring more particularly to the drawings the numeral 10 designates generally a chamber of any desired size and configura-

tion having an air inlet opening 11 at the base thereof.

Extending into the chamber 10 is a tank or reservoir 12 for containing fuel. The tank is out of communication with the chamber 10 and is closed at its top by means of a suitable closure 13.

Carried by the closure is a wick tube 14 for holding a wick 15, the wick extending into the tank 12.

Extending through the tank and out of communication therewith, is a tube 16 which has communication at its lower end with the chamber 10, preferably in alinement with the air inlet opening 11.

The tube 16 projects above the closure 13 and is provided with a tubular extension 17 secured in position in any suitable manner, preferably by being threaded on to the end of the tube 16 as at 18.

The extension 17 is provided with a slot 19 opening through the top thereof.

A nozzle 20 is provided with a body portion 21 having a reduced extremity 22. A gasket or packing element 23 is sleeved over the reduced portion 22, and a nut 24 is threaded upon the extremity of the reduced portion 22, and between which nut and a shoulder 25 of the body portion 21 the gasket is arranged.

A reducing nipple 26 is inserted into the extremity of the reduced portion 22 of the body 21 and the aperture in the nipple 26 is considerably less than the aperture through the nozzle 20, for a purpose to be hereinafter set forth.

The end of the body portion of the nozzle is inserted into the tubular extension 17 and is of a diameter to slidably fit therein and also in the tube 16, the nozzle being adapted to be raised and lowered in any suitable manner, such as by means of a handle 27 adjustably mounted upon a threaded projection 28 extending laterally from the body portion. The projection 28 is adapted to enter the slot 19 in the tubular extension 17 and by adjusting the handle 27 upon the extension 28 and against the extension 17, the nozzle may be secured in position.

The gasket 23 serves as a means for forming a fluid tight joint between the wall of the tube 16 and the exterior of the body portion 21 of the nozzle to prevent the escape of air. By adjusting the nut 24 so as to force the gasket 23 against the shoulder 25, the periphery of

the gasket will be projected beyond the periphery of the body portion so that it will frictionally bind upon the wall of the tube 16.

This gasket will also assist in maintaining the nozzle in its adjusted position to bind the nozzle against further movement.

The extremity of the nozzle is adapted to be positioned with respect to the flame sustained at the end of the wick 15, in accordance with the nature of the flame desired, and the work to be performed.

The structure thus formed is supported upon a suitable base 29, and interposed between the base 29 and the bottom of the chamber 10, is a bulb like device 30 preferably constructed of rubber, which is not only adapted to supply air to the chamber 10 and to compress the air therein but also serves as a handle by means of which the device may be transported as well as held in position for use. By reason of the fact that the bulb serves this double purpose it will be manifest that only one hand of the operator is necessary for both purposes so that the other hand will be free.

Air is supplied to the bulb through an opening 31 passing through the base 29, a valve 32 being provided for preventing the air from passing backwardly through the passage 31. A tube 33 connected with the passage 31, also has communication with the air inlet passage 11 of the chamber 10, and a valve 34 is provided for controlling the entrance of the air into the chamber 10 and out therefrom.

The valves 32, 34 are so arranged that when the bulb 30 is compressed, air will be delivered into the chamber 10, the compression of the bulb 30 serving to unseat the valve 34 and to seat the valve 32.

When the bulb 30 is released to permit the same to expand, suction will be created in the bulb which will seat the valve 34 and unseat the valve 32 to admit a new supply of air.

By alternately compressing and releasing the bulb 30, it will be manifest that air will be pumped into the chamber 10 and will be compressed therein, as the exit passage for the air from the chamber through the nozzle 20 is of a considerably less area than the air inlet 11.

By providing the reducing nipple 26, the exit of the air from the chamber 10 will be retarded, and by reason of the fact that there will then be some compressed air stored in the chamber 10, the blast of air emitted from the nozzle 20 will be sustained or continuous.

Means may be provided for controlling the valve 34 to prevent it from closing the passage 33 when the bulb 30 expands. To that end there may be provided a plunger 35 which is arranged in alinement with the valve 34 and is adapted to engage the valve and unseat the same by forcing it into a recess 36 in the connection 37 between the bulb 30 and the

air chamber 10. A stop device 38 is provided to limit the unseating movement of the valve 34 under the influence of the air pressure.

The plunger 35 may be operated in any suitable manner preferably by means of a cap or handle 39 which is preferably connected to the stem 40 of the valve, and the stem is provided with threads 41 engaging threads in the wall of the plunger casing 42.

By rotating the cap 39 the plunger 35 will be screwed forwardly and backwardly in the casing 42, and when moved forwardly the plunger will engage and unseat the valve 34, but when moved backwardly the valve 34 will assume a position upon its seat.

A packing element or gasket 43 and nut 44 similar to the gasket 23 and nut 24 may be provided for producing a fluid tight joint.

In the form of the invention shown in Figure 6 the valve 34 is controlled by means of a plunger 45, controlled by a spring 46, the plunger extending into the valve chamber 47 and being provided with operating handle 48.

In this form of the invention when it is desired to produce an intermittent discharge of air through the nozzle, the apparatus is inverted, and the plunger 45 retracted by drawing back upon the handle 48, until the valve 34 engages and rests upon the stop 38. The plunger is then released and the spring will cause the extremity of the plunger to pass under the valve 34, so that the valve will be held off of its seat when the apparatus is upright. When it is desired to produce a steady or sustained discharge of air from the nozzle 20 after the valve 34 has been once unseated, in the manner which is described, the plunger 45 may be retracted to allow the valve to fall to the position shown in solid lines in Figure 6.

In Figure 7 there is shown another form of means for raising and lowering the nozzle and for maintaining it in its adjusted position.

In this form of the invention a tubular extension 49 is connected with a nozzle 20, through the medium of a nut or collar 50 which is threaded on the end of the extension 49. A collar 51 is connected with the end 115 of the nozzle 20 and is provided with a reduced and externally threaded portion 52, to form a shoulder 53.

A disc 54 of suitable heat insulating material is sleeved upon the reduced portion 52 of the collar 51 to abut the shoulder 53, and the reduced portion 52 is threaded into the nut or collar 50 so as to clamp the disc 54 between the shoulder 53 and the collar 50.

If desired a pin or fastening device 55 may be provided for securing the disc against movement with respect to the collar 51. By grasping the disc 54 the nozzle may be raised or lowered as desired.

As a means for holding the nozzle in its

adjusted position there may be provided a packing 56 in an extension 57 on the cover 13, and through which extension the tubular member 49 passes.

5 An element 57 preferably of metal, is sleeved upon the extension 49 to engage the packing 56, and a bushing 58 is threaded upon the extension 57 and co-operates therewith to compress the packing 56 and frictionally bind the extension 49 in its adjusted position.

With this invention, it will be manifest that there is provided an apparatus by means of which a sustained or an intermittent flame 15 may be produced, according to the nature of the work being operated upon, and the nozzle may be adjusted to any desired extent to position it so that it will assume the desired position with respect to the flame.

20 It will also be manifest that the apparatus is of a unitary and compact construction, so arranged that it may be easily manipulated, and may be readily converted so that it will produce either an intermittent or a 25 steady or sustained flame.

While the preferred forms of the invention have been herein shown and described, it is to be understood that various changes may be made in the details of construction and in 30 the combination and arrangement of the several parts, within the scope of the claims, without departing from the spirit of this invention.

What is claimed as new is:—

35 1. A prosthetic lamp embodying an air chamber, a fuel chamber, one of which chambers is disposed within and out of communication with the other, a nozzle and flame sustaining means adjacent each other and having communication with the respective chambers.

40 2. A prosthetic lamp embodying an air chamber, a fuel chamber, one of which chambers is disposed within and out of communication with the other, a nozzle and flame sustaining means adjacent each other and having support for supplying air to the air chamber, said support maintaining said chamber, bulb and base against bodily lateral deflection one with respect to the other, said bulb serving as a handle whereby the entire apparatus may be lifted and held in position for use, by the same hand of the operator which collapses the bulb.

45 3. A prosthetic lamp embodying an air chamber, a fuel chamber, one of which chambers is disposed within and out of communication with the other, a nozzle and flame sustaining means adjacent each other and having a base for supporting the chambers, and a deflatable and inflatable bulb disposed between the base and said chambers for supplying air to the air chamber, means for maintaining the said base, bulb and chamber against bodily deflection one with relation to the other, said bulb serving as a handle

whereby the entire apparatus may be lifted and held in position for use by the same hand of the operator which collapses the bulb, the said bulb constituting a part and parcel of the supporting structure between said base 70 and chamber.

5. A prosthetic lamp embodying an air chamber, a fuel chamber, one of which chambers is disposed within and out of communication with the other, a nozzle and flame sustaining means adjacent each other and having communication with the respective chambers, a base for supporting the chambers, a deflatable and inflatable bulb disposed between the base and said chambers for supplying air to the air chamber, means for maintaining said bulb, base and chamber against bodily lateral deflection one with relation to the other, said bulb serving as a handle whereby the entire apparatus may be elevated and held in position for use by the same hand of the operator which collapses the bulb, and means controllable at the will of the operator for selectively causing the blast from the nozzle to be continuous or intermittent.

6. A prosthetic lamp including a nozzle, means for sustaining a flame adjacent the nozzle, an air chamber for supplying air to the nozzle, a supporting base, a standard connecting the chamber and said base, a deflatable and inflatable bulb disposed between the base and said chamber and encompassing the standard, said bulb serving as a handle whereby the entire apparatus may be lifted 100 and held in position for use by the same hand of the operator which collapses the bulb, and means whereby air will be forced into the said chamber when the said bulb is collapsed.

7. A prosthetic lamp including a nozzle, means for sustaining a flame adjacent the nozzle, an air chamber for supplying air to the nozzle, a supporting base, a standard connecting the chamber and said base, a deflatable and inflatable bulb disposed between the base and said chamber and encompassing the standard, said bulb serving as a handle whereby the entire apparatus may be lifted 110 and held in position for use by the same hand of the operator which collapses the bulb, and means whereby air will be forced into the said chamber through the said standard 115 when the said bulb is collapsed.

8. A prosthetic lamp including a nozzle, means for sustaining a flame adjacent the nozzle, an air chamber for supplying air to the nozzle, a supporting base, a standard connecting the chamber and said base, a deflatable and inflatable bulb disposed between 120 the base and said chamber and encompassing the standard, said bulb serving as a handle whereby the entire apparatus may be lifted and held in position for use by the same hand of the operator which collapses the 125 bulb.

bulb, means whereby air will be forced into the said chamber when the said bulb is collapsed, and means for selectively controlling the flow of air to cause the flow of air to the nozzle to be intermittent or sustained.

7. A prosthetic lamp including a nozzle, means for sustaining a flame adjacent the nozzle, an air chamber for supplying air to the nozzle, a supporting base, a standard 10 connecting the chamber and said base, a deflatable and inflatable bulb disposed between the base and said chamber and encompassing the standard, said bulb serving as a handle whereby the entire apparatus may be lifted and held in position for use by the same hand of the operator which collapses the bulb, means whereby air will be forced into the said chamber through the said standard when the said bulb is collapsed, and 15 means for selectively controlling the flow of air to cause the flow to the nozzle to be intermittent or sustained.

8. A prosthetic lamp including a nozzle, means for sustaining a flame adjacent the 20 nozzle, a support for the structure embodying a standard and a base therefor, a collapsible and inflatable bulb encompassing the standard above said base, and means whereby the deflation and inflation of the bulb will cause a supply of air to be delivered to the nozzle and against the flame, the said bulb serving as a handle by which the entire apparatus may be lifted and held in position for use by the same hand of the operator which collapses the bulb and while the bulb is being collapsed and inflated.

9. A prosthetic lamp including a nozzle, means for sustaining a flame adjacent the nozzle, a support for the structure embodying a standard and a base therefor, a collapsible and inflatable bulb encompassing the standard above said base, and means whereby the deflation and inflation of the bulb will cause a supply of air to be delivered 45 to the nozzle through the said standard and against the flame, the said bulb serving as a handle by which the entire apparatus may be lifted and held in position for use by the same hand of the operator which collapses the bulb and while the bulb is being collapsed and inflated.

10. A prosthetic lamp including a nozzle,

means for sustaining a flame adjacent the nozzle, a support for the structure embodying a standard and a base therefor, a collapsible and inflatable bulb encompassing the standard above said base, means whereby the deflation and inflation of the bulb will cause a supply of air to be delivered to the nozzle and against the flame, the said bulb serving as a handle by which the entire apparatus may be lifted and held in position for use by the same hand of the operator which collapses the bulb and while the bulb is being collapsed and inflated, and means for selectively controlling the supply of air to the nozzle to cause the flow to be intermittent or sustained.

11. A prosthetic lamp including a nozzle, means for sustaining a flame adjacent the 70 nozzle, a support for the structure embodying a standard and a base therefor, a collapsible and inflatable bulb encompassing the standard above said base, means whereby the deflation and inflation of the bulb will cause a supply of air to be delivered to the nozzle through the said standard and against the flame, the said bulb serving as a handle by which the entire apparatus may be lifted and held in position for use by the same hand of the operator which collapses the bulb and while the bulb is being collapsed and inflated, and means for selectively controlling the supply of air to the nozzle to cause the flow to be intermittent or sustained.

12. A prosthetic lamp including a nozzle, means for sustaining a flame adjacent the nozzle, a supporting base, a standard rising from said base and supporting the nozzle, an air chamber also supported by the standard for supplying air to the nozzle, a deflatable and inflatable bulb disposed between the nozzle and said base and encompassing the standard, said bulb serving as a handle whereby the entire apparatus may be lifted and held in position for use by the same hand of the operator which collapses the bulb, and means whereby air will be forced into the said chamber when the bulb is collapsed.

In testimony whereof I have signed my name to this specification, on this 28th day of April, A. D. 1926.

JACOB H. KAPLAN.
